SKIN DIVER'S HAND RAKE

Joseph Fedorka, Jr., 38 Meadowbrook Drive,
Somerville, N.J.

Filed June 26, 1963, Ser. No. 75,535

Term of patent 14 years

(Cl. D39—1)

FIG. 1 is a top plan view of a skin diver's hand rake showing my new design;

FIG. 2 is a side elevation thereof; and

FIG. 3 is an end elevation thereof.

The undisclosed underneath portion of the rake member is substantially the same in appearance as the top shown in FIG. 1.

I claim:

The ornamental design for a skin diver's hand rake, as shown and described.
